(57) **CLAIM**

The ornamental design for a faucet mount housing, as shown.

DESCRIPTION

FIG. 1 is a perspective view of a faucet mount housing showing our new design;

FIG. 2 is a front side elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view.

In the drawings, the broken lines depict environmental subject matter only and form no part of the claimed design.

1 Claim, 6 Drawing Sheets
